CLAIM

The ornamental design for a footwear sole as shown and described.

DESCRIPTION

FIG. 1 is a perspective view of the footwear sole embodying the new design;

FIG. 2 is a bottom view thereof;

FIG. 3 is a top view thereof;

FIG. 4 is a right side view thereof;

FIG. 5 is a left side view thereof;

FIG. 6 is an enlarged front view thereof; and,

FIG. 7 is an enlarged rear view thereof.

The dash-dash broken lines shown in the figures illustrate portions of the footwear sole that form no part of the claimed design.
